Paper Ruling Mach.

No. 30722. Patented Oct. 21, 1862.

UNITED STATES PATENT OFFICE.

THOMAS T. MORRELL, OF FARMINGTON, NEW HAMPSHIRE.

MACHINE FOR MAKING THE LEAVES OF BOOKS FROM A CONTINUOUS SHEET OF PAPER.

Specification forming part of Letters Patent No. 36,722, dated October 21, 1862.

To all whom it may concern:

Be it known that I, THOMAS T. MORRELL, of Farmington, in the county of Strafford and State of New Hampshire, have invented a new and Improved Machine for Making the Leaves of Blank-Books Complete from a Continuous Sheet of Paper; and I do hereby declare that the following is a full, clear, and exact description of the same, reference being had to the accompanying drawings, making part of this specification, in which—

Figure 1 is a perspective view of my machine. Fig. 2 is a perspective view of the reverse side of the same. Fig. 3 is a longitudinal vertical section. Figs. 4, 5, 6, 7, 8, 9, 10, 11, and 12 are details, which are fully explained as the description proceeds.

Similar letters of reference indicate corresponding parts in all the figures.

In the manufacture of blank-books it has heretofore been the practice to perform the several operations of cutting, folding, ruling, and paging the leaves by separate operations with distinct and separate machines for each, thus requiring considerable machinery and the attendance of one or more workmen to each machine, and consequently greatly enhancing the cost of the manufacture, besides involving the outlay of considerable capital to prosecute the business extensively and with success.

The object in view, therefore, in my invention is to combine the several operations in one and the same machine by a peculiar arrangement of certain devices for performing each operation in succession upon a continuous sheet of paper in its passage from a roll at one end of the machine to the other end of the same, in which the paper is first ruled upon both sides by means of two sets of fountain-pens, suitably arranged for that purpose; second, the paper is cross-ruled with column-lines into pages by means of rules arranged at appropriate distances asunder in the face of two rollers operating in connection upon each side of the paper; third, the pages thus formed are numbered by means of a peculiar device, which stamps the number of each page upon the upper corner thereof during the passage of the paper from one end of the machine to the other; fourth, the leaves are cut in folio form, one by one, from the continuous sheet; and, fifth, the leaves thus cut are folded and de-

posited regularly in their proper order, complete and ready for binding.

To enable others skilled in the art to make and use my invention, I will proceed to describe the same by means of the annexed drawings.

In the said drawings, H is the frame of my machine, at one end of which is arranged a roller, E, upon which the paper, g, (shown in blue lines,) which is to be formed into book-leaves is wound. (See Fig. 3.)

D' D are leveling-rollers, and A' A, at the opposite end of the machine, are drawing-rollers, which are revolved with equal velocity by means of two equal gears upon one end of the shaft of each roller and a pulley driven by a belt, (represented by the crank I in Fig. 1.)

The paper g passes between the rollers A' A, which are made to pinch the paper sufficiently to draw it from the roller E when they are revolved, being set together for that purpose by means of set-screws suitably arranged. (Represented in Figs. 1, 2, 3 of the drawings by the wedges i.) Above the roller E, I arrange a set of fountain-pens, h, Figs. 1, 2, 3, 4—such as are ordinarily used for the purpose—for ruling the under surface of the paper, and above the leveling-roller D', I arrange another set of fountain-pens, j, for ruling the upper surface of the paper. The first set, h, rule upon the roll of paper g, which is constantly diminishing in diameter by the unwinding of the paper, to provide for which the said pens h are arranged in a frame, f, which slides vertically in the upright portion of the frame H, as shown in Figs. 3 and 4, and the said pens are maintained in their proper relative position with the surface of the diminishing-roller E by means of the following surface-roller C, arranged in the frame f, and revolving by contact with the surface of the paper in unwinding.

In ruling a continuous sheet of paper upon both sides as it comes from another machine, which is desirable, I arrange the leveling-rollers D' D' D' as shown in Fig. 4, the pens h ruling the under side of the sheet, and the pens j ruling the upper side, in the same manner as in Fig. 3, the paper moving in the direction indicated by the arrows.

The cross-ruled or column-lining of the paper is performed by the ruling-rollers L L

consisting of two rollers of wood or metal, operating in connection and having an equal velocity, in the faces of which are inserted metal strips or rules $t\ t$, extending lengthwise of the rollers at the proper distance apart to rule the pages in the desired form, the rules in one roller being arranged to operate with plain surfaces $c\ c$ of sufficient width upon the other roller to effect an impression of the rules upon the paper in its passage between the rollers. The said rules t and plain surfaces c should be so arranged that their position upon the rollers $L\ L$ may be changed to suit the various forms of column-ruling. This may be done by securing them to the surface of the rollers $L\ L$ by screws passing through slots formed in the face of the rollers, or in any other well-known and effective way. The said rules are inked by contact with the ink-covered rollers $b\ b$ in revolving, which rollers are supplied and covered with ink, by means of the auxiliary rollers $2\ 2$, from a suitable fountain or ink-receptacle—such as is used for supplying ink to power printing-machines.

The number of the page is printed upon the upper corner of each by means of the types $r\ r$, &c., in the face of the cylinders $M\ N$, Figs. 1, 2, 3, and the entire apparatus which presents the said types $r\ r$ in their proper order and position to give the correct impression is clearly shown in detail in Figs. 3 and 5, and by sections in Fig. 6, which is an end view of the entire apparatus detached from the machine, Fig. 7 being a plan and section of the same, and Figs. 8 and 9 being details of the same, which will be presently explained in the proper place. This paging device consists of type-cylinders $M\ N$, secured upon spindles $F\ F$, and hung in frames $S\ S$, which are made to slide longitudinally upon the guide-rods $m\ m$, Fig. 3, by means of the cranks $a\ a$ and the connecting-rods $c\ c$, when the said cranks revolve.

Upon one end of each of the spindles $F\ F$ of the type-cylinders is formed a spiral groove, R , and the arrangement of the types $r\ r$ upon the cylinders coincides with the pitch of the said groove. The opposite end of each of the said spindles $F\ F$ is encircled with a spiral spring, s , Fig. 3, and upon each of the said spindles beside the cylinder is a ratchet-wheel, V , by means of which the spindle and cylinder are rotated intermittently by the vibrating movements of the ratchet u upon the arm w , the extreme ends of which arm slide in the inclined slits $h\ h$, with the sliding movements of the frame S . In the rotation of the type-cylinders the said cylinders are moved endwise by means of the screw or spiral groove R ; and against the face of the springs $s\ s$, which presents the successive numbers in order in one position with respect to the edge of the paper to be printed, and spring-pressure pads $5\ 5$, actuated by the inclined surfaces $t\ t$, formed thereon, coming in contact with the ends of the stationary arms $f\ f$, press the

paper against the face of the type and give the impression, as shown in Figs. 5 and 6. The arrangement and operation of the spiral groove R are clearly shown in Figs. 8 and 9. In each of these printing apparatuses, within the bearing formed for the spindle F in the frame S , Fig. 8, there is formed a circular recess for the reception of the dog n , (shown in red lines,) which traverses the spiral groove R in the act of moving the spindle endwise. This dog is attached to the trigger 4 by a pivot in the center of the hub Z of the frame, on which both turn. When the dog n is in the position shown in Fig. 8, it follows in the spiral groove R , and the spindle is moved endwise against the face of the spiral spring s , Fig. 3, and continues so to do until the trigger 4 comes in contact with the stud 6 in the movable collar 8 , which has the effect to turn the dog in the position shown in Fig. 9, when the spring s reacts and slides the spindle endwise in the direction indicated by the arrow, the dog n sliding in the straight groove T until the trigger 4 comes in contact with the stud 7, which places the dog n in the position shown in Fig. 8, in readiness to again traverse the spiral groove, and thus move the spindle endwise. It will be seen that the dog n turns in the space formed at the junction of the right groove with each turn of the spiral groove at $o\ o$, so that if it is not necessary that the spindle slide fully to the end to print the required number of pages the collar 8 may be fixed in the proper position to turn the dog n in either one of the said spaces o , and permit the return of the spindle when the required number of pages have been printed.

The types $r\ r$ upon the cylinder are inked by contact with the ink-covered roller P , which is supplied by the auxiliary roller 1^a from the fountain s' , Fig. 5, the said inking-roller being revolved by means of the gears $x\ x'$, the latter engaging with the gear y , which revolves with the ratchet-wheel V , Figs. 6 and 3.

One of the paging apparatuses, as above described, is arranged to print upon each side of the paper, as shown in Fig. 3, in which connection they have a reciprocating movement equal at the time the impression is made to the swiftness with which the paper moves, to avoid blurring the same.

The reciprocating movement of the paging apparatus produces the vibrating movement of the ratchet-arm w , caused by its sliding in the inclined slot h^2 or h^3 , Fig. 3. In paging books of but few pages the types may be arranged at greater distances asunder, and the ratchet-arm may have a greater range of motion to provide for the increase of distance between the types; or separate cylinders and ratchet-wheels, to correspond with any increase or decrease of distance between the types, may be substituted in paging leaves for different sizes of books.

This paging apparatus constructed and arranged substantially as above described, and

operating with a reciprocating movement, constitutes one feature of improvement in my machine.

In connection with the above-described paging apparatus, I arrange a cutting or shearing apparatus, a detached view of which is shown in Fig. 10, and consists of a sharp angular-edged blade, *k*, arranged in a reciprocating frame, *m*, which forms a flat table over which the ruled and paged sheet passes, as shown by the blue lines in Fig. 3. The said blade shears or cuts in connection with the square edge of the said table, and the blade is held uplifted by the springs *U*, one at each end thereof. A friction-roller arranged at each end of the top edge of the blade by contact with the inclined surface of the stationary projection *i* forces the blade down, and in so doing quickly severs the folio sheet from the end of the continuous sheet of paper. The reciprocating table slides upon suitable guides, *W*, by motion transmitted through the connecting-rod *N* from the crank *a*, which reciprocates the paging apparatus that prints the under surface of the paper.

It will be seen that the paging and cutting apparatuses are operated by the same cranks, and the two paging apparatuses by cranks of equal length of stroke, and that these two devices space off and divide the continuous sheet into folio leaves and pages as said sheet moves along by the action of the drawing-rollers *A A*, in consequence of which arrangement the width of the page and the size of the sheet depends upon the relative velocity of the cranks, which cut the said sheet at intervals once with each revolution, and the drawing-rollers *A A*, which carry the paper along during such intervals beneath the cutting device. Thus, if the velocity of the drawing-rollers be increased, more in length of the continuous sheet will be carried along before the cutter descends, and the sheet and pages will be larger, and vice versa.

The cutting apparatus, arranged and operating substantially as described, forms another feature of improvement in my machine.

The sheets thus cut from the continuous sheet are folded in folio form by means of the vertically-sliding folder *f*, in connection with the two folding-rollers *K K*, the said folder *f* consisting of a thin sheet of metal formed as shown in Figs. 11 and 12, and acting to double and carry the doubled edge between the folding-rollers; and in order that it may more surely perform this function I construct the said folder with an independent sliding piece, *j*, which is subjected to the action of a spring, *k'*, and I turn the rollers *K K* smaller at each end, as shown in Fig. 11, so that that portion of the folder upon each side of the independent sliding piece may be admitted between the rollers.

The spring *k'* presses the sliding piece *j* down, so that the edge of the latter is even with the lower edge of the folder, and the severed sheet being deposited beneath the folder, it descends, and, folding the sheet, carries it between the rollers, the portions *j''* upon each side of the folder *f* carrying the sheet on down as far as the center of the rollers, (see Fig. 11,) while the sliding piece is arrested by the stop *v* coming in contact with the cross-bar *s*, and held from passing between the rolls, though it affords the needed support to the sheet until it is seized by the revolving rollers. The folder is attached by connecting-rods *a x* upon each side to two levers, *h*, which communicate the required motion to the folder from the studs *r* in the face of the gears *g* upon each side of the machine. The folding-rollers have an equal velocity by being connected by two equal gears, *h'*, upon one end of each, and they are revolved by a pulley at the opposite end of one of them and a belt connecting with the pulley *H* on the driving-shaft, Fig. 2.

I am aware that a thin edge of metal has been previously employed to carry paper, &c., between two revolving rollers to effect the folding of the same; but I am not aware that a folder and a pair of rollers of the peculiar construction and arrangement shown and described have been before known or used.

The said construction and arrangement of the sliding folder and folding-rollers in combination, therefore, form another feature of improvement in my machine.

Having thus described my machine, what I claim as my invention, and desire to secure by Letters Patent, is—

1. In combination with one or more sets of fountain-pens for ruling the horizontal lines of a page, a set of ruling-rollers for printing the perpendicular lines, substantially as herein shown and described.

2. The reciprocating paging apparatus, arranged and operating substantially as shown and described, for the purpose specified.

3. The peculiar cutting apparatus, arranged and operating substantially as described, for the purpose specified.

4. The peculiar construction and arrangement of the folder *f* and the folding-rollers *P P*, substantially as shown and described, for the purpose specified.

5. The combination and arrangement of the several apparatuses comprising the within-described machine, whereby the successive operations may be performed in their proper order upon a continuous sheet of paper while in motion, substantially as herein specified.

THOMAS T. MORRELL.
